WASTE OUTLET FITTING

Abram N. Pasman, Milford, Conn.

Application June 19, 1943, Serial No. 491,435

10 Claims. (Cl 4—287)

This invention relates to equipment for lavatories, bathtubs, and the like, and more particularly to a waste outlet fitting embodying both a waste stopper construction and trap means for hair, lint, gems or other small articles that might pass the stopper, and clog the waste system.

A principal object of the invention is to provide a device of this character that will prevent clogging in a waste system.

Still another object of the invention is to provide a waste outlet fitting having a receptacle or trap from which articles accidentally dropped into the bowl or tub may be recovered readily.

A further object of the invention is to provide a simple fitting whose parts may be readily removed as a unit from the waste outlet for cleansing purposes, thus providing a sanitary construction.

Another object is to provide means whereby the parts may be removed as a unit from a body only in determined positions of the parts relative to said body so that they may be removed for cleaning or emptying of the receptacle or trap, but in normal use will not be removable from the body.

To the accomplishment of the foregoing and such other objects as may hereinafter appear, this invention consists in the novel construction and arrangement of parts hereinafter to be described and then sought to be defined in the appended claims, reference being had to the accompanying drawings forming a part hereof which shows, merely for the purpose of illustrative disclosure, preferred embodiments of the invention, it being expressly understood, however, that changes may be made in practice within the scope of the appended claims without digressing from the inventive idea.

In the drawings in which similar reference characters denote corresponding parts:

Figure 1 is a vertical section of the device with the parts in closed position;

Figure 2 is a similar vertical section showing the parts in open position;

Figure 3 is a transverse section taken along line 3—3 of Fig. 2 and viewed in the direction of the arrows;

Figure 4 is an elevational view of a detail;

Figure 5 is a bottom plan view of the detail of Fig. 4;

Figure 6 is a vertical section of a modified form of the device with the parts in closed position;

Figure 7 is a similar vertical section of the

modified device showing the parts in open position;

Figure 8 is a vertical section taken along line 8—8 of Fig. 7 of the removable unit; and

Figure 9 is an elevational view of a detail of this modified form of the device.

Referring to the drawings, and first to Figs. 1—5, inclusive, 10 denotes a tubular body adapted to be inserted in the drain opening of a lavatory, washbowl, tub, or the like. This body has an annular flange 11 which is adapted to seat around the mouth of the drain opening. It is provided, also, with an externally threaded portion 12. A clamping member, or lock nut, 13, threadedly engages the threaded portion 12 and serves to fasten the body 10 securely in the drain opening. Suitable sealing means, such as the ring 14, of rubber or other available packing material, is provided. A washer 15 of metal, or the like, lies between the ring 14 and the lock nut 13.

The body 10 is provided with a second threaded portion 16 for attachment thereof to a waste pipe or the like (not shown). An internally extending shoulder is provided for the body. This shoulder, in the embodiment shown, consists of an annular rib 17 formed on said body. Suitable overflow drain openings 10' are also provided in the body member.

The body 10 serves to receive the waste plug, valve or stopper member, 18. This member 18 is hollow and is admeasured externally to seat in its closed position upon a seat 19 provided on the body member 10. The stopper 18 has an internally-threaded portion 20. It also has an opening 21 in its top 22.

A lift member, or lever, 23 is provided for raising and lowering the stopper. This lever 23 has a ball portion 24 and a pair of arms 25, 25a. The ball portion 24 is rotatably supported within the stopper 18 and the manipulating arm 25 extends outwardly of the opening 24. Suitable packing 26 is provided around the ball 24 to prevent leakage. This packing is suitably pressed into sealing engagement with the stopper and the ball 24 by a washer member 27. The latter is pressed into place by a threaded ring portion 29a of a hollow guide member 29, the portion 29a being screwed into the threaded portion 20 of the stopper.

The guide member has a number of spaced prongs or feet 30 depending from the ring portion 29a. Transverse, parallelly-extending ribs 31 are provided between adjacent pairs of the prongs or feet 30 just below the ring portion 29a,

These ribs are reentrant at 31a appearing as chords of the ring member portion 29a in Fig. 5. The spacing between the ribs 30 is less than the diameter of the ball 24 and their upper inner edges 30b serve as abutments to retain the ball 24 within the stopper when the guide member 29 is assembled with the stopper. The arm 25a of the lever 23 extends into the space between the ribs 31a and is so admeasured in width that it prevents rotation of the ball member on a vertical axis but permits its rotation on a horizontal axis. The lower ends of the feet 30 are suitably joined by a guide ring 32. The described elements of guide member 29 are preferably a one-piece construction but may be individual parts suitably united to form the said guide member. The ring member 32 has an overall diameter admeasured to permit free but guiding movement of the guide member 29 within the body 10 so that guide member 29 as a unit guides the movement of the stopper 18.

A waste receptacle, or trap, 35 that acts as a strainer, is provided. This receptacle may be of any suitable construction. In Figs. 1-5, inclusive, it has cup-like form and is admeasured to lie within the body 10 with sufficient clearance between its outer surface and the inner wall of the body 10 to permit free drainage through its perforations 36. The strainer 35 is adapted to be supported from the shoulder 17. To this end, it has an annular flange 37 that rests upon the shoulder 17. This flange is provided with a suitable slot 38. A bayonet pin, or lug, 39 is provided on the wall of the body 10 adjacent the shoulder 17 so that seating of the flange 37 on shoulder 17 requires the slot 38 and stud 39 to be in alignment so that the flange can pass the pin 39. When the slot and pin are out of alignment the receptacle cannot be withdrawn from the body 10, as will be described more in detail hereinafter.

The receptacle, or strainer, 35 is provided in its bottom with a threaded opening 40 that lies substantially in the axis of said receptacle. A rod, or stud, 41 having a threaded reduced portion 42 is threaddedly supported in the opening 40 and extends substantially axially of the strainer to a point above the level of the flange 37. The rod 41 is suitably coupled to a portion 25b of the arm 25a of the ball lever 23 by a link 45. This link is pivoted at 46 to the rod 41 and at 47 to a portion 25b of the arm 25a. Thus, the waste receptacle 35 is in effect removably coupled to the lever 23.

The arm 25a has a nose 25c that is adapted to limit rotation of the ball 24 in one direction by abutment with the ring portion 29a of the guide member 29. The link 46 and the rod, or stud, 41 are so admeasured in length that, when the aforesaid abutment occurs, the pivot points 46, 47 are farthest apart in the axial direction of body 10, as shown in Fig. 2, and the stopper 18 is then lifted away from its seat 19. This represents the open position of the waste plug or stopper 18. The stopper or waste plug member is closed by grasping the manipulating arm 25 of the ball lever 23 and rotating the latter to move said arm 25 to the position shown in Fig. 1. This, through the action of link 45, causes the pivot point 47 to move axially toward pivot point 46 and causes the stopper to be moved into closed relationship on the seat 19 of the body 10. During movement of the stopper onto or off its seat 19, the guide member 29 serves to maintain the

stopper 18 in substantial alignment with said seat 19.

To clean or empty the basket or strainer 35, the manipulating arm 25 is grasped and rotated until slot 38 and pin 39 are in alignment. The assembled stopper 18 and waste receptacle 35 can then be removed as a unit from the body 10. The receptacle 35 is then unscrewed from the stud 41, emptied, and replaced thereon. The reassembled parts are put back into body 10 and rotated until the slot 38 and pin 39 are realigned. This permits the flange 37 to pass said pin 39 and reseat itself on shoulder 17. When this occurs, a further slight rotation of the stopper 18 misaligns the slot and pin and places the device in condition for use. In this condition the stopper and receptacle cannot be withdrawn from body 10. Thus, during use, the stopper and receptacle assembly will not be lifted out of body 10 when the arm 25 is grasped. In other words, means are provided by the slot-and-pin arrangement to retain the parts in position of use.

A modified form of construction is shown in Figs. 6-8, inclusive.

Referring to these figures, 100 denotes a tubular body substantially similar to the body 10. This body 100 has an annular flange 111 which is adapted to seat around the mouth of the drain opening. It is also provided with an externally-threaded portion 112. A clamping member, or lock nut, 113 threaded engages the threaded portion 112 and serves to fasten the body 100 securely in the said opening. Suitable sealing means, such as the ring 114, of rubber or other available packing material, is provided. A washer 115 of metal, or the like, lies between the ring 114 and the lock nut 113.

The body is provided with a second threaded portion 116 for attachment to a waste pipe or the like (not shown).

An internally-extending shoulder is provided for the body. This shoulder, in the embodiment shown, consists of a bead or ribs 117 formed on said body. Suitable overflow drain openings 110 are provided in the body member.

The body 100 serves to receive the waste plug or stopper member 118. This stopper is hollow and is admeasured externally to seat in its closed position upon a seat 119 provided on the body member 100. The stopper has an internally-threaded portion 120. It also has an opening 121 in its top 122. A lift member 123 is provided for raising and lowering the stopper. This member has a ball portion 124 and a pair of arms 125, 125a. The ball portion 124 is rotatably supported within the stopper 118 and the manipulating arm 125 extends outwardly of the opening 124. Packing 126 is provided around the ball 124. The ball 124, in turn, is suitably held within the stopper by a retainer member 127. The latter is held in place by a hollow guide member 128 which has a threaded portion 129a screwed into the threaded portion 120 of the stopper.

The guide member has a number of spaced prongs, or feet, 130. The member 129, too, is provided with ribs 131 on its external surface. In the embodiment shown, these ribs extend in alignment with the feet.

A waste receptacle, or trap, 135 that acts as a strainer, too, is provided. This receptacle may be of any suitable construction. In the embodiment shown, it has cup-like form and is admeasured to lie within the body 100 with sufficient clearance between its outer surface and the inner wall of the body 100 to permit free

drainage through its perforations 136. The strainer 135 is adapted to be supported from the shoulder 117. To this end, it has an annular flange 137 that rests upon the shoulder 117. This flange, likewise, may be provided with a slot 133 for the same purpose as slot 38. A bayonet pin, or lug, 134, similar to, and for the same purposes as, pin or lug 39, may be provided on the body 100.

The bottom of the receptacle has a reentrant groove 138 and a slot 139 arranged at substantially right angles with it. It also has an opening 140 that is substantially centrally located relative to the groove and the slot. A rod or stud 141, which has a reduced portion 142 that fits slidably in the opening 140, is provided. A spring 143 surrounds the reduced portion 142 and serves always to urge the rod away from the bottom of the strainer 135. A suitable limiting pin member 144 is positioned in the reduced portion 142 of the stud 141 and extends substantially transversely of the axis of the said stud 141. This pin is admeasured in length and diameter as to lie within the groove 138 in the assembled relationship of the parts and also to be capable of passing freely through the slot 139 when it is desired to remove the strainer 135 from the rod or stud 141. Such removal is effected by depressing the rod 141 so that the pin member 144 clears the groove 138 and by then rotating the strainer 135 to bring the pin member 144 into alignment with it. The pin member then can easily pass through the slot 139 and the strainer or basket 135 can then be removed from the rod 141.

The rod 141 is suitably coupled to the arm 125a of the ball lever 123 by a link 145. This link is pivoted at 146 to the rod 141 and at 147 to the arm 125a. Thus, the waste receptacle is in effect removably coupled to the lever 123, and thereby the stopper 118 and receptacle 135 are removable as a unit from the body 100.

The link 146 and the rod 141 are so admeasured that, when the pivot points 146, 147 are in axial alignment, as shown in Fig. 2, the stopper 118 is lifted from its seat 119. This represents the open position of the waste plug or stopper 118. The stopper or waste plug member is closed by grasping the manipulating arm 125 of the ball lever 123 and rotating the latter to move said arm 125 to the position shown in Fig. 1. This, through the action of link 145, causes the stopper to be moved into closed relationship on the seat 119 of the body 100. During movement of the stopper onto or off its seat 119, the guide member 130 and its ribs 131 serve to maintain the stopper 118 in substantial alignment with said seat 119.

To clean or empty the basket or strainer 135, the manipulating arm 125 is grasped and rotated until the slot 133 and pin or lug 134 are aligned. The assembled stopper 118 and waste receptacles 135 can then be removed as a unit from the body 100. The stud 141 is then pressed down against the resistance of spring 143 so that the pin 144 clears the groove 138. The perforated receptacle 135 is then given a turn sufficient to align the slot 139 and pin member 144. This will permit separation of the receptacle 135 and the stud 141 by the removal of the receptacle from the stud or vice versa. The separated receptacle now can be emptied and cleaned.

After cleansing, the receptacle is reassembled with the plunger 141 and the assembled unit is reinserted in the body 100.

With the devices described, simple, efficient constructions are provided with few working parts. Waste material is caught by the baskets or strainers 35 or 135 and retained therein for removal rather than passing to the drain pipe and causing clogging. Another advantage is that valuable articles, such as gems or the like, can be recovered from the strainers or baskets 35 or 135 as they will be retained by either. Moreover, another advantage of the invention is that the traps or receptacles 35 or 135 and their respective plugs 18 or 118 are removable as a unit from the device only in determined positions of the receptacles relative to the bodies 10 or 100, namely, when slots 38 or 133 register with lugs 39 or 134. In normal use of the device, as stoppers and traps in drain bodies 10 or 100, removal as units is prevented by the pins or lugs 39 or 134.

While specific embodiments of the invention have been disclosed, it must be understood that variation in structural detail within the scope of the appended claims is contemplated. There is no intention of limitation to the exact details of constructions shown and described.

I claim:

1. In a device of the character described, a body member having a seat, a waste plug member, an operating member pivotally supported within said plug member, a waste receptacle adapted to be positioned within said body, means for supporting said waste receptacle removably in said body member, and means for coupling said waste receptacle with respect to said operating member whereby manipulation of said operating member will serve to move said plug member relative to said seat.

2. In a device of the character described, a body member having a seat, a waste plug member, an operating member pivotally supported within said plug member, a waste receptacle adapted to be positioned within said body, means for supporting said waste receptacle removably in said body member below said plug member, a member extending from said receptacle, link means for coupling said last-named member to said operating member whereby manipulation of said operating member will serve to move said plug member relative to said seat, and whereby said plug member and said receptacle may be withdrawn as a unit from said body, and means for preventing such withdrawal except in one determined position of said receptacle with respect to said body.

3. In a device of the character described, a body member having a seat, a waste plug member, an operating member pivotally supported within said plug member, a waste receptacle adapted to be positioned within said body, means for supporting said waste receptacle removably in said body member below said plug member, means for coupling said waste receptacle with respect to said operating member whereby manipulation of said operating member will serve to move said plug member relative to said seat, and whereby said plug member and said receptacle may be withdrawn as a unit from said body, and means for preventing such withdrawal except in one determined position of said receptacle with respect to said body, said last-named means including pin and slot elements in conjunction with said body and said receptacle.

4. In a device of the character described, a body member having a seat, a waste plug member, an operating member having a ball portion,

said ball portion being rotatably supported in said plug member, a waste receptacle adapted to be positioned within said body, means for supporting said waste receptacle removably in said body member, means for coupling said waste receptacle with respect to said operating member whereby manipulation of said operating member will serve to move said plug member relative to said seat, and whereby said plug member and said receptacle may be withdrawn as a unit from said body, and means for preventing such withdrawal except in one determined position of said receptacle with respect to said body, said last-named means including a protuberance on said body member and a slot in a portion of said receptacle which must be aligned to permit withdrawal of the unit from said body.

5. In a device of the character described, a body member having a seat, a waste plug member, an operating member having a ball portion, said ball portion being rotatably supported in said plug member, a waste receptacle adapted to be positioned removably within said body, a member extending from said receptacle and separable therefrom, means for coupling said last-named member to said operating member and means for supporting said waste receptacle within said body member.

6. In a device of the character described, a body member having a seat, a waste plug member, an operating member having a ball portion, said ball portion being rotatably supported in said plug member, a waste receptacle adapted to be positioned removably within said body, a member threadedly engaging said receptacle and separable therefrom, means for coupling said last-named member to said operating member and means for supporting said waste receptacle within said body member, said waste plug member and said waste receptacle being removable as a unit from said body member.

7. In a device of the character described, a tubular body having a seat, a waste plug or stop-

per member, a lever pivotally supported in said stopper member, a stud member, a link connecting said lever to said stud member, a waste receptacle removably carried on said stud member, and means for removably supporting said waste receptacle within said tubular body, manipulation of said lever serving to raise and lower said plug or stopper member from said seat.

8. In a device of the character described, a tubular body having a seat, a waste plug or stopper member, a lever pivotally supported in said stopper member, a stud member, a link connecting said lever to said stud member, a waste receptacle removably carried on said stud member, 15 means for removably supporting said waste receptacle within said tubular body, manipulation of said lever serving to raise and lower said plug or stopper member from said seat, and means for guiding said stopper member during its raising and lowering.

9. In a device of the character described, a waste plug member for a waste outlet, a waste receptacle, a stud member, means for removably attaching said receptacle and said stud member to each other, an operating lever member, means for pivotally supporting and retaining said lever member within said plug member and link means coupling said stud member and a portion of said operating lever together.

10. In a device of the character described, a waste plug member for a waste outlet, a waste receptacle, a stud member, means for removably attaching said receptacle and said stud member to each other, an operating lever member, means 20 for pivotally supporting and retaining said lever member within said plug member and link means for coupling said stud member and a portion of said operating lever together, said means for removably attaching said receptacle and said stud member to each other including a pin member, 25 and a spring urging said pin member into engagement with a portion of said receptacle.

ABRAM N. PASMAN.
